UNITED STATES PATENT OFFICE

HENRY D. AKIN AND JAMES W. WILDER, OF GREENSBORO, NORTH CAROLINA
DESIGN FOR A GOLF-GAME UNIT OR SIMILAR ARTICLE

Application filed July 29, 1930. Serial No. 36,512. Term of patent 3½ years.

To all whom it may concern:

Be it known that we, HENRY D. AKIN and JAMES W. WILDER, citizens of the United States, residing at Greensboro, in the county of Guilford and State of North Carolina, have invented a new, original, and ornamental Design for a Golf Game Unit, or Similar Article, of which the following is a specification, reference being had to the accompanying drawing, forming part thereof.

game unit or similar article showing our new design.

We claim:

The ornamental design for a golf game unit or similar article, as shown.

HENRY D. AKIN.
JAMES W. WILDER.
